T. C. Harrison,

Lancet.

Patented June 20, 1836.

June 20, 1836 9747X 161.

Thomas H. Thompson
The Schedule referred to in this Letter Patent and making part of the
same containing a description in the name of the said Thomas H. Garrison
himself of his improvement in the Revolving Lancet.

Be it known that I Thomas H. Garrison of New Egypt,
county of Monmouth, and State of New Jersey, have invented an
improvement in the surgical arts, being a revolving surgical instrument
for performing incisions in surgical operations, called "Garrison's Revolv-
ing Lancet" which is described as follows, reference being had to
the annexed drawings of the same, making part of this specification.

This instrument consists of a small revolving cylindrical
cutter A having a circular steel cutter B about a eighth part inch
or more in diameter, fastened on one end of it, and at the other end is
attached a spring C similar to the mainspring of a Watch, which is
wound up in a barrel in the manner of a time piece by a key, ap-
plied to the end of the cutter which is made square and secured by
watch wheels & click. When an incision is to be made for bleeding
removing a tumor, or for any other purpose, the operator winds up
the instrument, lays bare the place to receive the incision, takes
the instrument between his thumb & forefingers - sets it in motion by
pressing upon the end of a lever which raises the click from the watch
wheel and suffers the spring to act which turns the cutter with the
cutter. He then applies the cutter to the spot to receive the inci-
sion and bears lightly upon it till the cut is made of the depth
required. The instrument is then ready. This instrument may be
regulated to the exact vicinity so as to make an incision of any length
or depth required by a steady hand. The cutter may be made cir-
cular or of any other figure required and may be turned, in the man-
ner described, or in any other mode preferred. What I claim is
my invention and which I desire to secure by Letter Patent,
consists in the method of performing incisions in surgical operations for
bleeding and for other purposes by means of a revolving cutter.
